UNITED STATES PATENT OFFICE.

ROBERT W. PRESCOTT AND HEMAN J. WHITTIER, OF KANSAS CITY, MISSOURI.

BROODING AND NESTING COOP.

952,355.

Specification of Letters Patent. Patented Mar. 15, 1910.

Application filed January 18, 1909. Serial No. 473,008.

To all whom it may concern:

Be it known that we, ROBERT W. PRESCOTT and HEMAN J. WHITTIER, citizens of the United States, residing at Kansas City, in the county of Jackson and State of Missouri, have invented certain new and useful Improvements in Brooding and Nesting Coops, of which the following is a specification.

This invention relates to brooding and nesting coops and more especially to that class capable of being transformed from operative to knock-down condition or vice versa, easily and quickly, our object being to produce a device of this character consisting of parts all bearing a hinged relation but incapable of detachment and misplacement.

A further object is to produce a coop of this character of simple, strong, durable and cheap construction.

With these objects in view the invention consists in certain novel and peculiar features of construction and organization as hereinafter described and claimed; and in order that it may be fully understood reference is to be had to the accompanying drawing, in which;

Figure 1, is a perspective view of a brooding and nesting coop embodying our invention. Fig. 2, is an enlarged vertical cross section of the coop. Fig. 3, is a horizontal section on a larger scale than Fig. 2, showing one end wall and parts of the side walls, bottom and roof in knock-down or folded relation. Fig. 4, is an enlarged vertical section taken on the line IV—IV of Fig. 1. Fig. 5, is an enlarged vertical cross section of a part of the coop to disclose more clearly the construction and arrangement of the cap-strip.

In the said drawing, where like reference characters identify corresponding parts, 1 indicates a brooding and nesting coop constructed as follows; 2 indicates gabled end walls of sheet-metal reinforced at their edges by stiffening wires 3, and secured to each end wall in the vertical plane of its apex and at its lower margin is a plate 4 provided with a pair of inwardly-projecting flanges 5.

6 indicates parallel side walls hingedly connected at 7 to the vertical margins of end walls 2 so that the side and end walls shall be capable of collapsing to a position analogous to that shown in Fig. 3, and hinged as at 8 to the side walls 6 at their lower edges,

are plates 9 which are adapted to occupy horizontal positions and conjointly constitute the floor of the coop. The inner edges of the floor plates 9 are stiffened by reinforce wires 10, and when folded down to horizontal position, rest upon the inwardly-projecting flanges 5 and in such position tend to prevent collapsing movement of the hinged walls, such collapsing movement being still further guarded against by providing one of the flanges 5, with upwardly-projecting points or pins 5^a for engagement with holes 9^a, in the floor plates 9.

11 indicates reinforce wires for the upper edges of side walls 6, and hinged to said wires are the roof-plates or sections 12 terminating at their upper or inner edges in stiffening rolls 13, adapted to rest near their ends upon the pitched upper edges of the end walls, the said roof-plates or sections being also provided with depending ribs 14 to fit snugly against the inner sides of the upper edges of end walls 2 so as to guard against collapsing movement and coöperate with the bottom plates in producing a substantial and rigid coop. The rolls formed at the inner or upper edges of the roof-plates provide a pair of external grooves 15 to receive the edges or tongues of a slidabie cap-strip 16 whereby said roof plates are held firmly together and the joint between them is bridged to exclude water from the coop. The said cap-strip has a central upwardly-projecting rib 17 provided with holes 18 to receive the ends of a wire handle 19 by which the coop can be readily handled when in "set-up" condition.

One end wall is provided at one side of its vertical center with an opening 20 of ample size for a hen to have ingress or egress to and from the coop, and pivoted at 21 adjacent to said opening, are an imperforate door 22, a skeleton door 23 and a foraminous door 24, either of said doors being capable of bridging the opening 20. When it is desired to prevent rain beating into the coop and also to protect the coop in stormy weather generally, the door 22 is closed. The door 23, is used to close the opening 20 when it is desired to keep the hen in but permit the little chickens to pass freely out of or into the coop. To exclude foxes, cats, rats and other rodents from the coop and prevent the hen or chickens from passing out and yet admit light and air to

the coop, the door 24 is used, it being obvious that in order to ventilate the coop it must be provided with ventilation holes, in this instance identified by the character 2^a and formed in the rear end wall, as shown in Fig. 2.

25 indicates a flanged shelf or hook projecting from the end wall provided with the opening, as a support for the doors when 10 open, a similar hook 26 being provided as a support for the doors when closed, it being understood of course that any suitable means, not shown, may be employed to fasten either of the doors in closed position, 15 if desired.

When it is desired to store or transport the coop, the handle 19 and cap-strip are removed. The roof-plates are then swung in the direction indicated by the arrows, 20 outward and downward to a vertically pendent position. The bottom plates 9 are then swung in the direction indicated by the adjacent arrows to a vertical position at the inner sides of the side walls 6, so that the 25 said side walls and plates 9 and 12 shall occupy substantially parallel positions. Pressure is then applied to cause the side walls and the end walls to collapse on their hinges 7 so that the walls 2 shall approximately extend in the same general direction as the walls 5, Fig. 3 showing a part of the 30 coop with the parts in a partially folded relation. When thus folded it is obvious that the coop occupies but little space and 35 that a great many of them in such collapsed condition, may be shipped at a minimum cost.

From the above description it will be apparent that we have produced a brooding 40 and nesting coop embodying the features of advantage enumerated as desirable and capable of modification in minor particulars without departing from the principle of construction involved.

45 Having thus described the invention what

we claim as new and desire to secure by Letters-Patent, is:

1. A device of the character described, comprising end and side walls hingedly connected together at their vertical edges, a 50 pair of bottom-plates hinged at their outer edges to the lower edges of the side walls and adapted conjointly to constitute the bottom of the coop, means carried by and projecting inward from the end walls and 55 underlying and supporting the bottom-plates when occupying a horizontal position, a pair of roof-plates hinged at their outer edges to the upper edges of the side walls and adapted to fold down upon the 60 end walls and conjointly form the roof of the coop, and formed with external parallel grooves adjacent to their meeting edges, and a slidably cap-strip fitting over the meeting inner edges of the roof-plates and slidably 65 engaging the said grooves of said plates; one of the end walls having an opening and a door to cover or uncover said opening.

2. In a brood coop, side pieces, and gabled end pieces hinged thereto, bottom pieces 70 hinged to said side pieces and adapted to turn outwardly from a floor position, means for retaining said bottom pieces in a floor position, top pieces hinged to said side pieces and adapted to turn against the side pieces 75 or rest on the gabled edges of the end pieces, and a ridge clamp for binding the top pieces together, the side pieces being adapted to fold against respective end pieces when the top and bottom pieces are folded there- 80 against, substantially as and for the purpose set forth.

In testimony whereof we affix our signatures, in the presence of two witnesses.

ROBERT W. PRESCOTT.
HEMAN J. WHITTIER.
